US0D1111010S

(12) **United States Design Patent** (10) **Patent No.:** **US D1,111,010 S**
(45) **Date of Patent:** **** Feb. 3, 2026**

(54) **SMART BRACELET**

(71) Applicant: **Beijing XinYouLingXi Technology Co., Ltd**, Beijing (CN)

(72) Inventor: **Jieming Wang**, Beijing (CN)

(73) Assignee: **Beijing XinYoulingXi Technology Co., Ltd.**, Beijing (CN)

(**) Term: **15 Years**

(21) Appl. No.: **29/882,728**

(22) Filed: **Jan. 18, 2023**

(51) LOC (15) Cl. **14-02**

CLAIM

The ornamental design for a smart bracelet, as shown and described.

DESCRIPTION

FIG. 1 is a first perspective view of a smart bracelet showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is another perspective view of the smart bracelet, shown in a state of use.

The broken lines shown in the drawings depict portions of the smart bracelet that form no part of the claimed design.

1 Claim, 9 Drawing Sheets
